UNITED STATES PATENT OFFICE

ELMER D. ABBOTT, OF SPRINGFIELD, OHIO, ASSIGNOR OF ONE-HALF TO
J. W. R. CLINE, OF SAME PLACE.

DESIGN FOR A CLAMP-BODY.

SPECIFICATION forming part of Design No. 29,974, dated January 10, 1899.

Application filed November 12, 1898. Serial No. 696,300. Term of patent 14 years.

To all whom it may concern:

Be it known that I, ELMER D. ABBOTT, a citizen of the United States, residing at Springfield, in the county of Clark and State of Ohio, have invented and produced a new and original Design for Clamp-Bodies, of which the following is a specification, reference being had therein to the accompanying drawings, forming part thereof.

- Figure 1 is a side elevation of a clamp-body showing my design. Fig. 2 is a top plan view; and Fig. 3, a sectional view on the line $x-x$ of Fig. 1, looking in the direction of the arrow.

As shown in the drawings, the leading or material feature of my design consists in the clamp-body formed in two planes, so that a portion of it has one elevation and another portion of it has another elevation, and in sloping the end A as illustrated.

- The outer outline of my design is composed of straight lines a , b , and c and curved lines d , e , and f . The straight line b runs in the same direction as the line c , but in a lower plane. The upper edge B of the clamp is slightly rounded, as illustrated in Fig. 3, and the sides of the body C taper outward from said edge, as clearly seen in Figs. 2 and 3.

Around the lower edges of the body part a bead-like projection D is formed, as illustrated in the drawings. This bead-like projection is similar in outline to the outer outline, as above described, and inasmuch as the inner edge E of the clamp conforms to the outline of the bead it will be understood that said edge is in different planes corresponding with the planes of the outer outline. A cross-bar F projects outward from the lower portion of the end A and tapers downward along its upper edges from said end, while its lower edge is curved, as shown at g in Fig. 3. The inner face of said cross-bar is tapered from its lower edge upward and outward, as also the inner face of the end A, as illustrated in Fig. 1.

What I claim as my invention is—
The design for a clamp-body, substantially as herein shown and described.

In testimony whereof I affix my signature in presence of two witnesses.

ELMER D. ABBOTT.
